(57) **CLAIM**

The ornamental design for a charging stand for vacuum cleaner, as shown and described.

DESCRIPTION

FIG. 1 is a front, top and right-side perspective view of a charging stand for vacuum cleaner showing my new design; FIG. 2 is a front view thereof; FIG. 3 is a rear view thereof; FIG. 4 is a top view thereof; FIG. 5 is a bottom view thereof; FIG. 6 is a right-side view thereof; FIG. 7 is a left-side view thereof; and, FIG. 8 is a perspective view shown in a state of use. In all drawings, the equal-length broken lines on the charging stand depict portions of the charging stand for vacuum cleaner that form no part of the claimed design. In FIG. 8, the equal-length broken lines that show a vacuum cleaner depict environmental subject matter and form no part of the claimed design. In FIG. 5, the dash-dot-dash broken lines define the boundaries of the claim. All broken lines form no part of the claimed design.
